(57) **CLAIM**

What is claimed is the ornamental design for a multi-tool, as shown and described.

DESCRIPTION

FIG. 1 is an elevated front left-side perspective view of a multi-tool showing our new design.

FIG. 2 is a depressed rear right-side perspective view of the multi-tool of FIG. 1.

FIG. 3 is a left-side elevational view of the multi-tool of FIG. 1

FIG. 4 is a top plan view of the multi-tool of FIG. 1.

FIG. 5 is a bottom plan view of the multi-tool of FIG. 1.

FIG. 6 is a right-side elevational view of the multi-tool of FIG. 1.

FIG. 7 is a front elevational view of the multi-tool of FIG. 1; and,

FIG. 8 is a rear elevational view of the multi-tool of FIG. 1. The broken lines in the figures depict portions of the multi-tool that form no part of the claimed design.

1 Claim, 4 Drawing Sheets
